(57) **CLAIM**

The ornamental design for an infinity chain link as shown and described.

DESCRIPTION

FIG. 1 is a top, front, right perspective view of a first embodiment of an infinity chain link showing my new design;

FIG. 2 is a bottom front right perspective view thereof;
FIG. 3 is a top plan view thereof, the bottom plan being identical thereto;

FIG. 4 is a front elevational view thereof, the rear elevational being identical thereto;

FIG. 5 is a right side elevational view thereof, the left side elevational being identical thereto; and,

FIG. 6 is a top, front, right perspective view with environmental subject matter.

FIG. 7 is a top, front, right perspective view of a second embodiment of an infinity chain link;

FIG. 8 is a bottom, front, right perspective view thereof;
FIG. 9 is a top plan view thereof, the bottom plan being identical thereto;

FIG. 10 is a front elevational view thereof, the rear elevational being identical thereto;

FIG. 11 is a right side elevational view thereof, the left side elevational being identical thereto; and,

FIG. 12 is a top, front, right perspective view thereof shown with environmental subject matter.

The portions of the infinity chain link shown in broken line form no part of the claimed design. The broken line showing of a link in FIGS. 6 and 12 is for the purpose of illustrating environmental subject matter and forms no part of the claimed design.
